UNITED STATES PATENT OFFICE.

WILLIAM H. WALKER AND WILLIAM H. McDEVITT, OF FENELTON, PENNSYLVANIA.

WORKING BARREL FOR OIL-WELLS.

955,024.

Specification of Letters Patent. Patented Apr. 12, 1910.

Application filed June 7, 1909. Serial No. 500,653.

To all whom it may concern:

Be it known that we, WILLIAM H. WALKER and WILLIAM H. McDEVITT, citizens of the United States of America, residing at Fenelton, in the county of Butler and State of Pennsylvania, have invented certain new and useful Improvements in Working-Barrels for Oil-WellS, of which the following is a specification, reference being had 10 therein to the accompanying drawing.

This invention relates to working barrels, and the invention has for its primary object to provide simple and effective means for simultaneously raising oil in the casing of a well and agitating the walls of the well at the lower end thereof, to increase the flow of oil and prevent the formation of paraffin and other matter.

A further object of this invention is to 20 provide a working barrel that can be used in connection with the present type of oil well casing and the pumping outfit.

These and such other objects as may hereinafter appear are attained by a working barrel that will be hereinafter described in detail and then claimed, and reference will now be had to the drawing forming part of this specification, wherein,

Figure 1 is a vertical sectional view of a 30 barrel constructed in accordance with our invention, Fig. 2 is a horizontal sectional view taken on the line W—W of Fig. 1, and Fig. 3 is a similar view taken on the line X—X of Fig. 1.

The working barrel consists of two cylindrical sections 1 and 2, having the ends thereof exteriorly screw threaded, whereby the sections can be connected by a coupling-piece 3, the casing 4 connected to the upper 40 end of the section 2, and a perforated semi-spherical hollow head 5 connected to the lower end of the section 1.

The section 2 is formed with a longitudinal bore 6 of the same length as said section 45 and the section 1 is formed with a longitudinal bore 8 of less length than the section 1, the bore 6 terminating at a point removed from the lower end of the section 1. The upper portion of the bore 8 is of greater 50 diameter than the lower portion. Said portion of greater diameter is indicated by the reference character 7, and which at its lower end provides a seat for a plug 14 which is formed with a stuffing box 15, the latter ex-

tending into the portion of smaller diameter of the bore 8. The lower end of the section 1 is formed with an opening 9 which at its upper end communicates with the lower end of a by-pass 10 formed in the said section 1. The upper end of the by-pass 10 opens into 60 the enlarged portion 7 of the bore 8 and above the plug 14. The bore 6 registers with the enlarged portion 7 of the bore 8.

Threaded in the lower end of the opening 9 is a valve seat 11 having a cage 12 for a 65 spherical ball or valve 13 adapted to seat by gravity.

Extending through the plug 14 and stuffing box 15 is a movable tubular piston rod 16, having the lower end thereof provided 70 with a piston head 17. The upper end of the piston rod 16 extends into the bore 6 and is perforated, as at 18. Connected to the upper end of the rod 16 as at 19 is a valve seat 20, serving functionally as a piston head 75 within the bore 6. The valve seat 20 is provided with a cage 21 for a spherical ball or valve 22, and said cage is connected, as at 23, to a pump rod 24.

The section 1 at its lower end is formed 80 with a plurality of radially-disposed openings 25 which at their inner ends communicate with the lower portion of the bore 8.

In operation—an upstroke of the pump rod 24 causes the valve 13 to open, and oil 85 to enter the opening 9, by-pass 10, and the enlarged end of the bore 8 above the plug 14. Oil also enters the openings 25 into the lower end of the bore 8. A downstroke of the pump rod 24 causes the piston head 17 90 to eject the oil within the lower part of the bore 8 and causes the valve 13 to close. Oil within the enlarged end 7 of the bore 8 is then forced into the tubular piston rod 16, raising the valve 22 and entering the 95 casing 4 or that part of the bore 6 above the valve seat 20. Another upstroke of the pump rod 24 causes the valve 13 to open and the valve 22 to close, and the operation 100 continues as above described when the rod 24 is reciprocated.

While in the drawings there is illustrated a preferred embodiment of the invention, we would have it understood that the structural elements thereof can be varied or changed, as to the size, proportion and manner of assemblage without departing from the spirit of the invention.

Having now described our invention, what we claim as new, is;—

1. A working barrel for oil wells comprising two sections, the upper of which is provided with a bore of a length equal to the length of its section and the lower of which is provided with a bore of less length than the length of its section, the bore of the lower section having its upper portion enlarged and registering with the bore of the upper section, means for connecting the two sections together, and said lower section having an opening at the bottom thereof for the entrance of the oil, said lower section provided with a by-pass communicating at its lower end with said opening and at its upper end opening into the enlarged portion of the bore of the lower section, for conducting the oil from the opening to the enlarged portion of the bore, a plug mounted in the enlarged portion of the lower section, a tubular piston rod extending through said plug and having the upper portion thereof perforated, a piston carried by the lower end of said rod, a piston head carried by the upper end of the rod and provided with a valve mechanism, a gravity valvular device mounted in said opening at the bottom of the lower section, said lower section provided with a series of openings communicating with the lower portion of the bore in the section whereby the oil in the lower portion of the bore in said section will be ejected therefrom against the walls of the well at the lower end thereof to increase the flow of oil and prevent the formation of

paraffin and other matter, and a pump rod connected with the valve mechanism carried by the piston head.

2. A working barrel for oil wells comprising an upper and a lower section suitably connected together, each of said sections provided with a bore, said bores registering with each other, a plug in the bore of the lower section, said lower section at its lower end formed with an opening for the entrance of the oil, a valvular device mounted in said opening, said lower section having a by-pass for establishing communication between said opening and that portion of the bore of said lower section above the plug for conducting oil thereto from said opening, a piston rod extending through said plug and having its lower end provided with a piston, a movable gravity valve carried by said piston rod and arranged in the upper section, and said lower section provided with openings communicating with the bore of said section whereby the oil in the lower portion of said bore will be ejected therefrom on the down stroke of the piston against the walls of the well to prevent the formation of paraffin and to increase the flow of oil.

In testimony whereof we affix our signatures in the presence of two witnesses.

WILLIAM H. WALKER.
WILLIAM H. McDEVITT.
